UNITED STATES PATENT OFFICE.

MELVILLE F. WEBSTER, OF ROCKVILLE CENTER, NEW YORK, ASSIGNOR OF ONE-HALF
TO ROBERT E. LEIGH, OF NEW YORK, N. Y.

LUBRICATING DEVICE.

1,199,951.

Specification of Letters Patent.

Patented Oct. 3, 1916.

Application filed November 6, 1915. Serial No. 59,989.

To all whom it may concern:

Be it known that I, MELVILLE F. WEBSTER, a citizen of the United States, residing at Rockville Center, in the county of Nassau and State of New York, have invented a new and useful Lubricating Device, of which the following is a specification.

This invention relates to lubricating devices, and is designed more particularly for 10 use in connection with elevator guide rails, although capable of more extended use.

The object of the invention is to provide an oiling device which will supply oil to the 15 guide rails only when the elevator is in motion and will return all excess of oil to the reservoir, besides maintaining the oil in a clean condition.

In accordance with the present invention, 20 an oil container, oil being considered as the lubricant used, is mounted on the elevator adjacent to each guide rail, and journaled in the reservoir so as to project therefrom into contact with the guide rail is a roller. The mounting for the roller is so arranged 25 as to readily yield to side movements of the elevator with respect to the guide rail and to have a constant tendency to gravitate toward the side rail while the roller serves as a propelling means for an oil elevating 30 structure entering the body of lubricant in the body of the reservoir or container and lifting such oil to the roller. Furthermore, provision is made for ready access to the interior of the reservoir and to the journal 35 bearings of parts therein so that the reservoir and turning parts may be cleansed when needed and fresh lubricant supplied as occasion demands.

The invention will be best understood 40 from a consideration of the following detailed description, taken in connection with the accompanying drawings forming part of this specification with the further understanding that while the drawings show a practical form of the invention, the latter 45 is not confined to any strict conformity with the showing of the drawings, but may be changed and modified so long as such changes and modifications come within the 50 scope of the appended claims.

In the drawings:—Figure 1 is a vertical section through the lubricant reservoir showing the adjacent guide rail for the elevator in elevation. Fig. 2 is a plan view of 55 the reservoir with the top plate removed

and the guide rail shown in cross section. Fig. 3 is a section on the line 3—3 of Fig. 2 with the moving parts omitted. Fig. 4 is a section on the line 4—4 of Fig. 3.

Referring to the drawings, there is shown 60 a guide rail 1, which rail is of customary T form in cross section.

Mounted on the elevator, which latter is not shown in the drawings, adjacent to each guide rail 1, is a container or reservoir 2, the 65 container shown in the drawings being of substantially square cross section and elongated in the direction of its length but such particular shape is not at all obligatory. At the upper end, it being understood that the 70 container is customarily installed upright, there is a projecting neck 3 forming a marginal shoulder 4 about the container to receive a cap 5 with marginal depending flanges 6 surrounding the neck 3, whereby 75 the cap is held in place and dust and dirt are excluded. That upright wall of the container 2 directed toward the guide rail 1 is provided with a through passage 7 and for convenience of description that upright side 80 provided with the passage 7 will be considered as the front of the container.

On the inner wall of opposite sides of the neck 3, recesses 8 are formed by surrounding flanges 9. Each recess 8 has its bottom 85 rounded as shown at 10 to constitute a bearing for the corresponding end of a rod 11 extending across the reservoir 2 from side to side, and normally lodged in the recesses 8 is a rod 11 extending across the reservoir. 90 The rod 11 carries an endless web 12 preferably of wicking, of a length to reach close to the bottom of the container 2, which latter when in operation is provided with a quantity of lubricant indicated at 13. This 95 lubricant is of any desired nature and as it should be normally liquid any suitable lubricating oil may be used and consequently for convenience of description, the term oil will be employed.

The neck 3 close to the front of the reservoir has angle recesses 14 defined by flanges 15. The angle recesses 14, have rounded bottom ends 16 seating corresponding ends of a rod 17 carrying at its central portion 105 spaced arms 18 having angle extensions 19 extending on opposite sides of the web 12 and at the ends remote from the arms 18 provided with a junction piece 20 which may or may not be integral therewith. 110

Mounted in the angles of the arms 18, 19 is a pin 21 carrying a roller 22 between the arms 18, said roller being of a size to extend through the passage 7, and bear 5 against the stem member of the T guide rail 1, which member is the active guiding tread of the guide rail. The roller 22 is preferably, however, not necessarily made of fiber such as vulcanized fiber, but may of 10 course be made of other suitable material.

In the normal position of the reservoir 2 with relation to the guide rail 1, which position is somewhat closer than illustrated in the drawings, the junction end 20 of the 15 arms 19 is sufficiently raised to cause the arms 19 to extend at a slight rising angle toward the back of the reservoir while the arms 18 have a corresponding angle to the vertical. There is therefore a constant tendency for the roller or wheel 22 to bear against the guide rail 1 under the action of gravity. This tendency may be increased 20 by enlarging the connecting member 20 or otherwise adding weight thereto as by a separate weight 23 shown in Fig. 1 and hung from a connecting member 20. Furthermore, the gravity action tends at 25 all times to automatically accommodate the wheel 22 to variations in the distance of the reservoir from the guide rail as frequently 30 occurs in the running of an elevator.

In practice the space between the front of the reservoir and the guide rail may be about $\frac{3}{8}$ of an inch but when the arms 18 are 35 parallel with the front of the reservoir, such space will be about $\frac{5}{8}$ of an inch, wherefore considerable margin is provided for side movement of the elevator with relation to the guide rails. The pin 11 supporting the 40 wick may revolve, that is it may act as a wheel, but by using a pin excessive speed of movement of the wick is prevented.

While a vulcanized fiber oiling wheel 22 has been referred to, it will be understood 45 that it may be constructed of other materials, including metals, or it may be so formed as to have a peripheral portion of metal. Such an oiling wheel does not take up an excess of oil from the wick, but only 50 such as will cling to the wheel by capillary attraction and such oil is transferred to the guide rail, producing thereon only an extremely thin film of oil, but ample for the purpose, while any excess of oil is returned 55 to the wick, to be wiped off from the roller by the wick. The result is that only sufficient oil is transferred to the guide rail to 60 keep the latter in a properly lubricated condition, a very thin film of oil being suitable for the purpose. There is, therefore, no waste of oil and a very economical use of oil. Whenever access to the interior of the 65 reservoir is desired, it is only necessary to lift off the cap 5, and then the parts within the reservoir may each be bodily removed

without the necessity of tools or the unfastening of any holding devices.

It will be observed that the roller, which may be taken as indicative of one or more rollers, has a pendulum mounting imparting to it the constant tendency to move into engagement with the guide rail and to follow up or yield to all side movements of the elevator. Furthermore, the oil feeding wheel 22 being of a non-absorptive material 70 carries the lubricant by capillary attraction 75 only and hence is inactive to convey the oil from the reservoir or wick to the guide rail when the elevator is standing still.

What is claimed is;—

1. A lubricating device for the guide rails of elevators, comprising a reservoir for lubricating material adapted to be mounted on an elevator car, a transfer roller for the lubricating material pendently mounted in 80 and extending to the exterior of the reservoir and having its center of gravity in the installed position of the device on that side of the vertical line of the axis of swing of the pendulous mounting remote from the 85 respective guide rail, whereby the roller has a constant tendency to gravitate toward said guide roller, and lubricant feeding means within the reservoir in position to carry lubricant from a supply thereof in the reservoir to the said transfer roller. 90

2. A lubricating means for the guide rails of elevators comprising an oil reservoir adapted to be mounted on an elevator car in operative relation to a guide rail, a transfer 100 roller pendulously mounted within the reservoir and extending therefrom to the guide rail and provided with means for imparting a constant tendency by gravity to the roller to engage the guide rail and a pendent band 105 of absorbent material in the reservoir extending into the portion of the reservoir designed to contain a supply of oil and in position to be engaged by the transfer wheel.

3. A lubricating device for the guide rails 110 of elevators comprising a reservoir for oil, connected spaced angle arms pivotally mounted therein in pendent relation to the pivot, a transfer roller carried by the arms and projecting from the reservoir into position to engage the guide rail with the arms and roller related to the pivot support of the arms to impart by gravity a constant tendency to the roller to engage the guide rail, and oil elevating means within the 115 reservoir in position to be engaged and actuated by the transfer roller. 120

4. A lubricating device for the guide rails of elevators comprising a reservoir for oil, connected spaced angle arms pivotally 125 mounted therein in pendent relation to the pivot, a transfer roller carried by the arms and projecting from the reservoir into position to engage the guide rail with the arms and roller related to the pivot support of 130

- the arms to impart by gravity a constant tendency to the roller to engage the guide rail; and oil elevating means within the reservoir in position to be engaged and actuated by the transfer roller, the reservoir having a readily removable cover and being provided with supports for the oil elevating means and for the arms from which they may be freely lifted.
- 10 5. A lubricating device for the guide rails of elevators, comprising an oil reservoir adapted to be mounted on the elevator car, a pendulously mounted oil transfer roller of non-absorbent material mounted in the reservoir and projecting therefrom to en-

gage the guide rail, and freely hanging oil feeding means of absorbent material within the reservoir and engaged by the roller for raising oil from a supply thereof within the reservoir to said transfer roller, the latter 20 carrying oil reaching it from the absorbent material to the guide rail solely by surface capillary attraction.

In testimony that I claim the foregoing as my own I have hereto affixed my signature in the presence of two witnesses.
